UNITED STATES PATENT OFFICE.

THOMAS R. McKNIGHT, OF AURORA, ILLINOIS, ASSIGNOR TO WESTERN WHEELED SCRAPER COMPANY, OF AURORA, ILLINOIS, A CORPORATION OF ILLINOIS.

DUMP-CAR.

1,154,261.

Specification of Letters Patent. Patented Sept. 21, 1915.

Application filed July 27, 1914. Serial No. 853,441.

To all whom it may concern:

Be it known that I, THOMAS R. McKNIGHT, a citizen of the United States, residing at Aurora, in the county of Kane and 5 State of Illinois, have invented certain new and useful Improvements in Dump-Cars, of which the following is a specification, reference being had to the accompanying drawings.

10 My invention relates to dump-cars in which the car bed is arranged to be dumped at either side by the use of compressed air supplied through train-pipes and controlled from the cab of the locomotive, and it has 15 for its object to provide means by which any desired car or cars which it is not desired to dump may be conveniently cut out so that the rest of the cars in the train may be dumped independently of the car or cars so 20 cut out.

A further object is to provide means by which the cutting out of any car or cars may be accomplished from either side of the train and from either end of each car.

25 I accomplish these objects as illustrated in the drawings and as hereinafter described.

That which I believe to be new is set forth in the claims.

In the accompanying drawings, Figure 1 is 30 a side elevation of a dump-car illustrating my improvements; Fig. 2 is a plan view illustrating such improvements; and Fig. 3 is a detail, being a partial side elevation of a part of the cut-out mechanism.

35 Referring to the drawings, 4 indicates the under body of the car, which is equipped with cylinders 5—6 at opposite sides and near its opposite ends, by the admission of air to which the car bed is dumped at one

40 side or the other of the track. The mechanism by which the admission of air to the cylinders 5—6 effects the dumping of the car bed forms no part of my present invention and is therefore not illustrated in detail.

45 Reference, however, may be made to Letters Patent No. 1,063,276, granted June 3, 1913, as illustrating one form of mechanism which may be advantageously employed for that purpose.

50 7—8 indicate train-pipes connected, respectively, with the cylinders 5—6 by branch pipes 9—10, as shown in Fig. 2. Said branch pipes are provided with valves 11—12 which, when opened, operatively connect the dumping mechanism with the respective

train-pipes 7—8, and when closed, cut off such mechanism from the train-pipes. The stems of the valves 11—12 are provided with levers 13—14 by which they may be conveniently operated.

50 15 indicates a lever, one end of which is pivoted at 16 on the under body of the car near one end thereof. The free end of said lever is connected by a connecting-rod 17 with a rod 18 which is connected to the lever 13 and also to one arm of a bell-crank lever 19 pivoted at 20, as shown in Fig. 2.

15 21 indicates an operating-rod connected to the other arm of the bell-crank lever 19 and extending at one side of the car so that it 70 may be conveniently grasped by the operator when it is desired to rock the lever 19 to open or close the valves 11—12. It will be apparent that in the construction shown, by pulling out the operating-rod 21 the bell-crank lever 19 will be rocked so as to swing the valve-lever 13 to the right. Movement of the operating-rod 21 in the opposite direction will turn the valve to the left.

25 22 indicates a lever fulcrumed intermediate at 23 on the under body of the car, near its opposite end, and connected at one end by a connecting-rod 24 with the lever 15 at the opposite end of the car. At the opposite side of its fulcrum the lever 22 is connected by a connecting-rod 24^a with a rod 25 which connects the valve-lever 14 with a bell-crank lever 26 pivoted at 27 upon the under body of the car. The other arm of the lever 26 is provided with an operating-rod 28 which projects at the opposite side of the car from the operating-rod 20, as shown in Fig. 2.

35 90 From the foregoing description it will be 95 seen that when the operating-rod 21 is operated to turn the valve 11 to the right, the lever 15 will also be swung to the right, and through the connecting-rod 24 the lever 22 will be actuated to pull the connecting-rod 25 to the left. The valve 12, being at the opposite side of the car, will accordingly be turned in a direction corresponding to that in which the valve 11 is turned. Similarly, movement of the operating-rod 21 in the 100 opposite direction operates both valves reversely. In the same way, both valves may be operated by operating the operating-rod 28. Thus, the operator may open or close both valves 11 and 12 from either side of the 105 car or from either end thereof, and so cut 110

off both cylinders 5—6 simultaneously from the train-pipes, or connect them therewith, as may be desired. This, of course, does not interfere in any way with the flow of air 5 through the train-pipes.

That which I claim as my invention, and desire to secure by Letters Patent, is,—

1. The combination with a dump-car having dumping cylinders for dumping the car 10 at one side or the other respectively and means connected with said cylinders for supplying compressed air thereto, of valves for controlling the admission of compressed air to said cylinders, and means whereby said 15 valves may be simultaneously opened or closed.
2. The combination with a dump-car having dumping cylinders for dumping the car at one side or the other respectively and 20 means connected with said cylinders for supplying compressed air thereto, of valves for controlling the admission of compressed air to said cylinders, and devices at opposite sides of the car adapted to be actuated to 25 simultaneously open or close both valves.

3. The combination with a dump-car having dumping cylinders for dumping the car at one side or the other respectively and 30 means connected with said cylinders for supplying compressed air thereto, of valves for controlling the admission of compressed air to said cylinders, and devices at opposite ends of the car adapted to be actuated to 35 simultaneously open or close both valves.

4. The combination with a dump-car having dumping cylinders for dumping the car at one side or the other respectively and 40 means connected with said cylinders for supplying compressed air thereto, of valves for controlling the admission of compressed air to said cylinders, levers adjacent to the op-

posite ends of the car, means connected with said levers respectively for opening or closing said valves when said levers are actuated, and means for actuating said levers 45 simultaneously.

5. The combination with a dump-car having dumping cylinders for dumping the car at one side or the other respectively and 50 means connected with said cylinders for supplying compressed air thereto, of valves for controlling the admission of compressed air to said cylinders, levers adjacent to the opposite ends of the car, means connected with said levers respectively for opening or closing 55 said valves when said levers are actuated, and bell-crank levers connected with said first-mentioned levers for actuating the same.

6. The combination with a dump-car having dumping cylinders for dumping the bed in one direction or the other, train-pipes connected respectively with said cylinders, valves between said train-pipes and said 60 cylinders, and means for simultaneously 65 opening or closing said valves.

7. The combination with a dump-car having dumping cylinders for dumping the bed in one direction or the other, train-pipes connected respectively with said cylinders, 70 valves between said train-pipes and said cylinders, levers at opposite ends of the car, means connecting said levers with said valves respectively, and means connecting 75 said levers together whereby said valves are operated in unison by the actuation of said levers.

THOMAS R. McKNIGHT.
